UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

ELASTIC-FLUID TURBINE.

No. 856,426.

Specification of Letters Patent.

Patented June 11, 1907.

Application filed December 22, 1905. Serial No. 292,902.

To all whom it may concern:

Be it known that I, FREDERICK SAMUELSON, a subject of the King of Sweden, residing at Rugby, England, have invented certain new and useful Improvements in Elastic-Fluid Turbines, of which the following is a specification.

This invention relates to steam turbines and has for its object to provide simple and efficient means for separating moisture from the steam in its passage through a turbine of the multi-stage type, thereby preventing the loss in efficiency arising from the presence of moisture in the steam during its passage through the turbine.

The accompanying drawing which is a part sectional view of a multi-stage turbine of the Curtis type, clearly illustrates one method of carrying my invention into effect.

In the drawing 1 represents the turbine casing, 2 the shaft and 3 the rotating elements or wheels carrying the fluid receiving vanes or buckets 4 on their peripheries. Each of the wheels 3 is shown as provided with three rows of buckets and interposed between these rows are stationary buckets 5 secured to the casing 1.

The turbine illustrated is a two-stage machine and the steam is delivered into each of the stages through nozzles 6, which may be expanding or non-expanding in character.

The nozzles of the second stage are secured on the underside of a diaphragm 7 separating the first from the second stage. On the upper side of diaphragm 7 is secured an inclined annular partition 8 which overhangs the distributing nozzles 6 of the second stage and extends for some distance toward the axis of the turbine, so that the steam as it is discharged from the first wheel is caused to flow radially inward toward the turbine shaft and then outward under the partitions 8 to the nozzles of the second stage. Any moisture in the steam instead of passing radially inward with the steam is thrown outward by centrifugal force and collects in an annular depression or channel 9 formed at the periphery of the diaphragm 7. By thus deflecting the steam in its passage between stages the moisture is effectively separated and the steam is delivered to the succeeding stage in a dry condition.

The water which collects in the channel 9 may be discharged from the turbine but I

prefer to provide drainage channels 10 some 55 or all of which may be fitted with stop-cocks 11. These channels discharge the water into an annular chamber 12, the water passes through passages 13 on to the diaphragm of the second stage. Some of the water which 60 is thus drained off from the first to the second stage is caused to evaporate owing to the lower pressure and the steam so produced does useful work in passing through the remaining stages of the turbine. 65

Steam or other elastic fluid is admitted by the chest 14 containing one or more admission valves. In the present illustration of my invention a plurality of valves are employed, each under the control of an electro-magnet 15.

Mounted in the base of the turbine is a condenser 16, and between the condenser tubes and the last wheel is a wall or diaphragm 17 slanting toward the shaft and 75 forming a part of the condenser casing. It is provided with suitable openings, shown in dotted lines, to enable the steam to pass to the condenser tubes. This wall may also be employed to direct the steam in any desired 80 manner through the condenser.

Although I have particularly described my invention as applied to a two-stage turbine of the Curtis type it will be obvious that it is equally applicable to turbines having 85 more than two stages and also to any vertical type.

In accordance with the provisions of the patent statutes, I have described the principle of operation of my invention, together 90 with the apparatus which I now consider to represent the best embodiment thereof; but I desire to have it understood that the apparatus shown is only illustrative, and that the invention can be carried out by other means. 95

What I claim as new and desire to secure by Letters Patent of the United States, is,—

1. In an elastic-fluid turbine which is divided into stages, the combination of fluid-discharging devices, wheel buckets acted 100 upon by the fluid from said devices, and an annular device which causes the fluid exhausting from one stage to flow inwardly toward the shaft to discharge moisture in so doing, and to flow outwardly to the fluid-discharging devices of a lower-pressure stage. 105

2. An elastic-fluid turbine of the multi-stage type having means for preventing

moisture from passing with the fluid from one stage to the next comprising an annular inclined partition overhanging the inlet nozzles of a stage so that the fluid has to pass inward toward the axis of the turbine and then outward to the nozzles, the liquid being thrown outward while the elastic fluid is passing inward, substantially as described.

3. In an elastic-fluid turbine of the multi-stage type, the combination of inlet nozzles, an inclined annular plate overhanging the inlet nozzles between one stage and the next succeeding stage, an annular channel surrounding said plate, and passages leading from said annular channel to the succeeding stage, substantially as and for the purposes described.

4. In an elastic-fluid turbine which is di-

vided into stages of expansion, fluid-discharging devices and wheel buckets for each stage, and a means for separating moisture from the fluid as it flows from one stage to another, comprising a plate for suddenly changing the direction of flow, one or more passages receiving the liquid discharged from the fluid and that flowing over the plate, and a means in a stage of lower pressure for collecting the liquid and discharging it at a point or points out of the normal path of the entering fluid.

In witness whereof, I have hereunto set my hand this 7th day of December, 1905.

FREDERICK SAMUELSON.
